UNITED STATES PATENT OFFICE.

WARREN E. WILLIS, OF NORTH ATTLEBORO, MASSACHUSETTS, ASSIGNOR TO E. I. FRANKLIN & CO., OF NORTH ATTLEBORO, MASSACHUSETTS, A COPARTNERSHIP CONSISTING OF WALLACE G. FRANKLIN, CLARENCE W. FISHER, AND ELTON B. FISHER.

BUCKLE.

1,375,880.

Specification of Letters Patent. Patented Apr. 26, 1921.

Application filed February 7, 1921. Serial No. 442,966.

To all whom it may concern:

Be it known that I, WARREN E. WILLIS, a citizen of the United States, residing at North Attleboro, in the county of Bristol 5 and State of Massachusetts, have invented certain new and useful Improvements in Buckles, of which the following is a specification.

My invention is an improvement upon the 10 well known clamp buckle and is particularly designed for use in belt buckles.

In the drawings:

Figure 1 is a side elevation of a clamp belt buckle, in clamping position;

15 Fig. 2 is a similar view, in open position; Fig. 3 is an under or inside plan view of Fig. 1;

Fig. 4 is a section through the clamping end of a buckle, with my improved connection;

Fig. 5 is a detail cross sectional view, on an enlarged scale, on line 5—5 of Fig. 4;

Fig. 6 is a similar view on line 6—6 of Fig. 4;

25 Fig. 7 is a perspective view of the clamp member;

Fig. 8 is a perspective view of the pintle and tube;

Fig. 9 is a perspective view of the old style 30 clamping member;

Fig. 10 is a perspective view of a simple embodiment of my invention.

In belt buckles of the clamping type, such as illustrated in the drawings, (Figs. 1 to 35 3 inclusive) one end of the strap or belt X is secured to the handle or loop, h, of the clamping member, and the free end of the strap is passed through the body member B while the clamp is in open position, and 40 the clamping jaw H is then turned to engage the strap X and clamp it between the jaw and the body B. The clamping member as heretofore used consisted of a clamping jaw H, a handle h, and lugs h', all integral (see 45 Fig. 9). The lugs were engaged by ears b, formed upon the sides of the body B.

It is obvious that the perfect clamping efficiency of such a device will be dependent, in a degree, upon the thickness of the strap, 50 If the strap is of exactly the right thickness the clamping jaw can be turned into a position substantially at right angles to the strap and will engage it perfectly. If the strap is thicker, the parts will be put under consider-

able strain in the clamping operation. If 55 the strap is still thicker it will not be possible to turn the clamping member into a clamping position which it can hold in use.

Belts employing clamping buckles, such as are shown are usually assembled by the 60 dealer, who purchases straps of various lengths and buckles of varying designs and materials and assembles to suit the customer.

In practice leather belt straps which are 65 cut from a hide, vary greatly in thickness, with the result that clamping buckles, of the type shown in the drawings, in many cases work imperfectly. If the clamp is designed for a thick strap, it fails to clamp a thin strap and if designed for a strap of minimum thickness it may be impossible to turn 70 it to a self-holding clamping position when a thick strap is used. The dealer must therefore carry a larger stock of straps and select by experiment a strap combining the right 75 factors of length and thickness to operate well within the buckle selected or must have a range of size in the clamping member in every style buckle.

It is the object and effect of my invention 80 to provide a self-adjusting or compensating clamp belt buckle, which will clamp equally on thick or thin straps, within a wide range of variation, with the result that the dealer need stock only the minimum number of 85 straps and buckles, for any buckle will fit any strap.

It will be observed that as heretofore made the pivot end, h², of the clamping member with its lugs h¹ integral, these lugs 90 engaging ears b upon the body B, formed a stiff and unyielding connection (see Fig. 9). In my improved clamping buckle the pivot portion of the clamping member carries no integral lugs. The pivot portion or 95 end of the clamping member is bored longitudinally as at 1, Fig. 10, and is then undercut as at 2, Fig. 10. A flexible pintle 3, is then inserted the ends of the pintle pass through the ears b on the body and 100 connect the body and the clamp.

Viewed from the upper or outer side, the buckle appears to be identical with the old style buckle, but it will be apparent that, when the jaw H is in engagement with the 105 strap the pintle is unsupported at the undercut portion 2 of the pivot end h² and the flexible pintle, when force is applied to the

clamping jaw H, may flex slightly, the ears b holding the ends of the pintle and the mid portion of the pintle rising slightly with the clamping member. This action takes place when a strap somewhat thicker than the normal minimum thickness is employed.

In the best mode of applying my invention I do not bore and undercut the pivot ends h² of the clamping member, as described above, but groove the upper or outer surface of the pivot end h² as at h³ (see Fig. 7). In this groove I lay a small tube 4, undercut at its ends, as at 2. Through this tube is passed a flexible pintle 3 and the assembly is then fixed in the groove h³. The undercut side of tube 4 faces the pivot end h², the result is that the pintle is in contact with the long side and the short side of tube 4, and that a semi-circular space 41 is formed between pintle 3 and the groove h³, equal in thickness to the thickness of the walls of tube 4, at that part of the pintle which extends beyond the short side of the tube 4. When pressure is applied to clamp H the pivot-end h² is forced up and the pintle 3 may be flexed, but when the flexure is sufficient the pintle will contact near its ends, with the ends of groove h³, thus changing the fulcrum point and practically neutralizing the flexibility of the pintle and preventing any damaging flexure.

I claim:

1. In a buckle, a body part; a clamping member having a relatively short bearing for a pintle adjacent the clamping jaw; a flexible pintle engaging the relatively short

bearing and the body part, to connect the two parts with capacity for rotative and reciprocal relative movement, substantially as described.

2. In a buckle, a body part; a clamping member having a tubular bearing for a pintle adjacent the clamping jaw, open at its ends on one side of the bearing; a flexible pintle engaging the tubular member and the body part, to connect the two parts with capacity for rotative and reciprocal relative movement, substantially as described.

3. In a buckle, a body part; a clamping member having a relatively short bearing for a pintle adjacent the clamping jaw, formed as a tube and secured to the body of the clamping member; a flexible pintle engaging the relatively short bearing and the body part to connect the two parts with capacity for rotative and reciprocal relative movement, substantially as described.

4. In a buckle, a body part; a clamping member having a tubular bearing for a pintle adjacent the clamping jaw and a relatively short bushing in the tubular bearing upon one side; a flexible pintle engaging the tubular bearing and the body part, the pintle being supported at its mid portion by the bushing, all combined and organized to connect the two parts with capacity for rotative and reciprocal relative movement with a predetermined limiting stop to the reciprocal relative movement, substantially as described.

Signed at North Attleboro, Massachusetts, this first day of February, 1921.

WARREN E. WILLIS.
